UNITED STATES PATENT OFFICE.

WILLIAM P. WOODS, OF BIRMINGHAM, ALABAMA, ASSIGNOR TO JAMES R. MCWANE, OF BIRMINGHAM, ALABAMA.

METAL BENDING AND STRAIGHTENING MACHINE.

Application filed December 12, 1924. Serial No. 755,526.

This invention relates to metal bending and straightening machines.

The object is to provide a machine for use in bending metal bars, pipes, rails or other analogous metal bodies of elongated form wherein it is desired to give only a slight bending action for the purpose of straightening the same; and the invention is designed especially for use in pipe foundries for the purpose of straightening metal core bars which have become defective through rough usage, warping or other causes.

Another object is to provide a simply and cheaply constructed machine for this purpose which may be readily set up to occupy a minimum amount of space, the underhung form of structure bringing certain parts close to the ground level and enabling the same to be located within a pit formed for the purpose, thus providing a very low structure with no superimposed parts to hinder the application of core bars or the like to the machine for straightening the same or their removal therefrom, and permitting an unobstructed view at the top of the core bar to enable the operator to sight along the same to detect irregularities therein.

A further object is to provide means in connection with the bending means proper whereby abutment blocks or anvils may be interposed between the main support of the machine and the core bar or other work to be straightened, so as to confine the bendable area of the same close to the bending means, and to enable the operator to remove said blocks or anvils so that a general bending or straightening of the bar from end to end may be obtained.

A final object is to provide a strong and durable machine of this character wherein a single operator, who may be seated at one end of the machine, may direct or guide the core bar into position on the machine, may readily move the bending mechanism in either direction longitudinally of the core bar to locate the same over a bend or hump, may readily revolve the core bar to bring such bend or hump on the top thereof to a position where it may be most easily and quickly detected, and may readily control hydraulic means for imparting a powerful downward pull on the bending means to straighten the core bar.

A full and complete understanding of the

invention may be obtained from a consideration of the following detailed description, taken in connection with the accompanying drawings forming a part of this specification, it being understood that while the drawings show a practical form of the invention, the latter is not to be confined to strict conformity with the showing thereof, but may be changed or modified, so long as such changes or modifications mark no material departure from the salient features of the invention, as specifically pointed out in the appended claims.

In the drawings, in which similar reference characters designate corresponding parts throughout the several figures:—

Figure 1 is a side elevation of the improved bending machine;

Figure 2 is a top plan view of the same;

Figure 3 is a transverse sectional view, some parts being omitted;

Figure 4 is a detail vertical section through the operating cylinder;

Figure 5 is a detail perspective view showing the manner of mounting the control valve;

Figure 6 is a detail section showing the manner of supporting the pressure hose;

Figure 7 is a horizontal section taken on the line 7—7 of Fig. 1.

Referring to the drawings there is shown a main supporting member in the form of a length of I-beam 1, which is preferably formed of a large size so as to provide sufficient strength to withstand the heavy strains incident to the straightening of pipes, core bars, rails, etc.

The form of the machine shown and described herein is that used in the treatment of core bars, but it will be clear that the other articles mentioned may also be treated thereon.

The I-beam 1 is of a length to accommodate the maximum length of core bars, and by the adjustment of certain parts to be described, may be adapted for use on shorter length bars. The beam is elevated and supported somewhat above the ground level by end sills 2, preferably formed of wood and to which the beam is rigidly fastened by suitable plates or clips 3 or by any other means.

The sills 2 are located adjacent to the ends of the beam, and a shallow pit or trench 4 is

formed in the ground between said sills for the purpose of accommodating certain depending parts of the device, and which enables the top part of the machine to be kept relatively close to the ground level, thus economizing in overhead space and providing a machine well beneath the eye level of the operator, even while the latter is seated at one end of the machine.

10 Secured to the top face of the upper flanges of the I-beam 1, and located over the sills 2, are core bar seats or pillow blocks 5 formed of suitable hard metal, and having their lower portions secured to adjustable 15 head blocks 6 provided with suitable flanges at the base thereof for the reception of bolts or other fasteners 7, which hold the head blocks in position on the beam 1. One of the head blocks, say the left hand one as 20 viewed in Figure 1 of the drawings, may be adjusted toward or away from the opposite end for the purpose of adapting the same for supporting longer or shorter core bars.

The core bar 8 is provided near its bell 25 end with the usual annular groove 9, which rests in the arcuate seat of the adjacent pillow block, while the elongated, imperforate portion 8^a at the opposite or spigot end of the core bar is adapted to rest within the 30 seat 5 at that end of the machine.

Transverse plates 10 and 11 are held together beneath the underface of the lower flanges of the I-beam by means of side plates 12, which are bolted to the same and have 35 their inner opposed edges in close proximity to the edges of said flanges (Figs. 1 and 2).

Bolted to the underside of the plate 10, which is somewhat longer than the plate 11, is a hydraulic cylinder 13 of suitable construction, while the said plate 11 carries a pair of downwardly extending and inwardly directed arms 14, preferably formed of a single length of suitable iron and constituting hangers, the lower ends of which are in 40 close relation to each other and provided with aligned pivot openings.

A piston rod 15 extending through the lower end of the cylinder 13, is connected by a pair of links 16 to one end of a horizontally disposed lever 17, which is fulcrumed at its opposite end between the lower ends of the aforesaid hangers 14, by means of a pivotal bolt 18, said lever being located within the trench or pit 4, as shown in Figure 1 of the drawings.

Opposite vertical pull bars 19 are located at each side of the I-beam 1, in close proximity to the outer free edges of the upper and lower flanges thereof, the said pull bars 50 extending up above the upper face of the said beam or support 1, and passing through suitable slots in the side plates 12, are bent below the latter so as to approach each other, where they are held in rigid spaced 55 relation by cross bolts 20 having suitable

spacing sleeves, and at the lower ends are adapted to receive the aforesaid lever 17 at an intermediate point of the same, to which they are pivotally connected by a pin 21.

Within the cylinder and connected to the rod 15, which passes through a gland 23, is the usual piston 22 adapted to be actuated in a vertical direction by fluid under pressure entering through one or the other of upper and lower ports 24 and 25, respectively 75 mounted in the heads of the cylinder and connected to fluid supply hose 26, passing back on opposite sides of the I-beam or main support to the operator's end of the same, as shown to the right in Figure 1 of the drawings.

The plates 10, 11 and 12 being joined together and adapted to move together form, in effect, a carriage slideable on the I-beam from one end to the other of the pit 4, and when said carriage is moved, by means to be described, to a position remote from the operator, the supply hose is extended, and when the said carriage is drawn in the opposite direction, said hose is prevented from falling into the pit, to interfere with the passage of the depending parts of the carriage and from becoming entangled otherwise, by means of hangers 27 riding along beneath the lower face of the I-beam and 90 suspended by rollers 28 bearing on the lower flanges of the same, the hose being held to the hangers by suitable clips 29, as clearly shown in Figure 6.

The hose 26 extends to the operator's end 100 of the machine, where they are in communication with a three-way valve 30, mounted on a laterally extending plate 31 bolted to the under face of one of the upper flanges of the I-beam and at the extreme end thereof. The valve 30 is provided with a supply hose 32 and an exhaust port 33, the valve proper being under control of the operator by means of a handle 34, which may be turned to admit fluid pressure through the 105 valve and into the upper inlet port 24 of the cylinder to force the piston downwardly, at which time the valve 30 permits the lower port 25 of the cylinder to exhaust the lower portion thereof through the opposite hose 110 26 out through the exhaust port 33 to the atmosphere, and by moving the handle in the opposite direction, the fluid under pressure is admitted to the lower cylinder port to lift the piston and the upper port thereof 115 exhausts into the atmosphere through said exhaust port 33.

In order to render easy the passages of the aforesaid carriage backwardly and forwardly, the same is suspended by opposite pairs 125 of hangers in the form of angle plates 35, securely bolted to the front and rear marginal portions of the plates 10 and 11 respectively, said hangers having anti-friction rollers 36 mounted thereon to ride upon the 130

upper faces of the lower flanges of the I-beam.

A cable or other flexible member 37, passing over sheaves 38 suitably journaled at opposite ends of the I-beam and on one side of the web thereof, is adapted to shift the carriage from one end of the pit to the other, the ends of said cable being secured to the hangers 35, and that sheave adjacent to the operator being equipped with a suitable crank 39 for the purpose.

The upper ends of the pull bars 19 on opposite sides of the I-beam are provided with spaced eyes 40, between which there is adapted to be engaged the ends of a curved bending bail 41, by means of removable pins 42 passing through said eyes 40 and a suitable aperture in the ends of said bail. The bail, in action, extends across and bears upon the top of the core bar 8 and, when the piston is forced downwardly, pulls down on the core bar to correct any irregularities therein in an obvious manner. In placing the said core bar in position on its seats or supports 5, the bending bail is swung outwardly by removing one of the pins 42, (as indicated in dotted lines in Figure 3), when the said bar may be readily applied in position or removed therefrom.

In some instances where a core bar is generally curved or warped throughout its entire length, the pull of the bending bail 41 when located approximately at the center of the core bar with the latter supported at its ends only upon the seats 5, will serve to correct the defect; but it often happens that such bars are irregularly bent and warped into relatively small humps or hollows at different points along their lengths by the action of repeatedly heating and cooling under the influence of the molten metal; it being understood that the core bars in question are what are known as permanent core bars and are used again and again for holding the core sand in the mold. For the purpose of straightening such bars, the same must be supported below at points relatively close to the bending bail so that the bending area of the bar is confined to a short distance or length, when said humps or hollows may be straightened out by turning the core bar beneath the bending bail in an appropriate manner by means to be described.

To this end the upper ends of the pull bars 19 on one side of the I-beam are provided with pairs of forwardly and rearwardly directed ears 43, between which are pivoted blocks 44 by means of vertical pins 45 passing through said ears. To the outer faces of said blocks there are pivoted, by pins 46, the inner ends of swinging arms 47, which curve inwardly toward their free ends to lie over the I-beam and are there provided with longitudinal slots 48. The slots 48

receive headed pins 49 secured in anvil blocks 50, of a length substantially equal to the distance between the upper face of the I-beam and the core bar, and relatively wide so as to form a broad and sure bearing for the said bar when the same is pulled down by the bending bail 41. The blocks 50 are preferably formed of wood, such as oak, and may be easily and cheaply renewed when they become worn.

When the carriage is moved either forwardly or backwardly by means of the crank and cable to locate the bending bail at the desired point above a rise or hump in the core bar, the blocks 50 are also drawn into proper position to coact therewith, and as the pull bars 19 are drawn downwardly by the piston and the lever 17 to effect the bending or straightening, the pivots 46 and 49 and slots 48 permit the levers 47 to partake of such downward movement while the blocks 50 remain stationary under the pressure thus caused. The vertical pins 45 also permit the blocks 44, arms 47 and anvils 50 to be swung outwardly from between the main support or I-beam and the core bar, as clearly shown in Figure 7, when it is desired to give the entire core bar a general bending.

For the purpose of turning the core bar so that humps or rises may be brought on the upper side thereof, a simple crank 51 may be utilized, said crank having an extended shank to be inserted into the spigot end of the pipe, at the operator's end of the machine, to be held therein by a wedge 52, preferably formed of oak wood, which may be lightly driven into position to bind the core bar to the shank of the crank.

From the foregoing it will be seen that a simple, cheaply constructed and strong and durable straightening machine has been provided for correcting inequalities in elongated metal bodies or castings, which may be actuated and controlled by a single operative, and which occupies a minimum amount of space.

What is claimed is:—

1. A metal bending machine comprising a longitudinal supporting member, means at the ends of said member to support the article to be bent, a frame slidable on said member, power means carried by said frame, bending means connected to said power means and engaging over the top of said article, anvil blocks at each side of said bending means for engaging the underside of said article, means for flexibly connecting the anvil blocks to said bending means to permit the bending means to act independently of said blocks, said flexible connecting means permitting said blocks to be shifted to one side in a horizontal plane away from the article being bent when it is desired to bend the entire article, and means for moving said slidable frame together with the

power means, the bending means, and the anvil blocks along the entire length of the article.

2. A metal bending machine, comprising a longitudinal supporting member, supports located at the ends of said member to support the article to be bent, a frame slidably mounted on said member, power means carried by said frame, bending means connected to said power means and engaging over the top of said article, anvil blocks located at each side of the bending means and engaging beneath said article, connecting means between said blocks and said bending means, said connecting means having two movements at right angles to each other, permitting the bending means to move downwardly without affecting the position of the blocks, and also supporting the blocks when swung outwardly in a horizontal plane from beneath the article when it is desired to bend the article from end to end, and means for moving said slidable frame, the power means, the bending means and said anvil blocks as a unit along said article.

3. A metal bending machine comprising a longitudinal support, pillow blocks mounted thereon for supporting the article to be bent, a depending cylinder having a piston and mounted to slide along the support, means pivoted beneath the support to slide with the cylinder and having connection with the piston, vertically slidable pull bars pivoted to said means, and a bending bail pivoted at one end to one of the vertical pull bars and adapted to be swung over said article and engaged with the other pull bar to bend the article downwardly when the piston is actuated.

4. A metal bending machine comprising a longitudinal support, pillow blocks mounted thereon for supporting the article to be bent, a depending cylinder having a piston and mounted to slide along the support, means pivoted beneath the support to slide with the cylinder and having connection with the piston, vertically slidable pull bars pivoted to said means, and a bending bail pivoted at one end to one of the vertical pull bars and adapted to be swung over said article and engaged with the other pull bar, longitudinal arms carried by said pull bars, and anvil blocks swivelled to the outer ends of said arms and adapted to rest on the longitudinal support and to bear against the article adjacent to the bending bail to support the article when the bail is pulled downwardly by the action of the said piston.

5. A metal bending machine comprising a longitudinal support, pillow blocks mounted thereon for supporting the article to be bent, a depending cylinder having a piston and mounted to slide along the support, means pivoted beneath the support to slide with the cylinder and having connection with the

piston, vertically slidable pull bars pivoted to said means, and a bending bail pivoted at one end to one of the vertical pull bars and adapted to be swung over said article and engaged with the other pull bar, ears formed on the upper end of said pull bars, vertically swivelled blocks mounted between the ears, longitudinally disposed arms horizontally pivoted at their inner ends to said blocks and having horizontal slots at their outer ends, and anvil blocks horizontally pivoted in said slots and normally resting upon the longitudinal support in position to bear against the underside of the article to permit the pull bars and bending bail to move downwardly under the action of the piston.

6. A metal bending machine comprising a longitudinal support, pillow blocks mounted thereon for supporting the article to be bent, a depending cylinder having a piston and mounted to slide along the support, means pivoted beneath the support to slide with the cylinder and having connection with the piston, vertically slidable pull bars pivoted to said means, and a bending bail pivoted at one end to one of the vertical pull bars and adapted to be swung over said article and engaged with the other pull bar, forwardly and rearwardly extending arms carried by said pull bars, universal joints connecting the same thereto at points above the longitudinal support, anvil blocks swivelled to the outer ends of said arms and adapted to bear between the longitudinal support and said article, said blocks being adapted to permit the vertical movement of the pull bars, to slide longitudinally therewith or to be swung laterally and off of the longitudinal support when it is desired to give the article a general bend from end to end.

7. A metal bending machine, comprising a longitudinal supporting member, upstanding article supports located at the ends of said member, a frame slidably mounted on the supporting member, a vertical, depending cylinder carried by the frame, a hanger carried by the frame adjacent the cylinder, a piston provided with a piston rod and mounted in the cylinder, a lever connected at its terminals to the piston rod and the hanger, an upstanding, slideable yoke connected at its lower end to an intermediate part of the lever, a bail connected to the upper end of the yoke and adapted to be locked over the article to be bent, and means for controlling fluid pressure in the cylinder to cause the bail to bend the article.

8. A metal bending machine, comprising an elongated main support, article rests located at each end thereof, a carriage mounted to slide longitudinally along the main support, a cylinder and a hanger depending from the carriage in spaced relation, a piston rod extending from the lower end of

the cylinder, means connecting the hanger and the piston, pull bars also connected at their lower ends to said connecting means and extending upwardly in straddling relation to and above the main support, a swinging bending bail pivoted to the upper end of one pull bar and having detachable connection with the other to permit the same to bridge the article, anvil blocks carried by

6 one pull bar and universally jointed thereto to bear under the article and upon the main support to confine the bending action of the bail, means located at one end of the support for moving the carriage in either direction.

9. A bending machine comprising a main support formed of an I-beam adapted to be supported at each end, means on each end for supporting the article to be bent, a carriage arranged below and having wheels adapted to roll along the lower flanges of the beam, bending means mounted to slide vertically and adapted to engage over the article, means for exerting a downward pull 20 on said bending means and controllable from one end of the I-beam, spaced anvil blocks to confine the bendable area of the work and removable from the latter to give a general bending, said blocks being mounted on the 25 top of said I-beam, and means for moving the carriage with the bending means and the blocks, said moving means being located at one end of said beam to enable the operator to sight along the article and move the bending means to the point desired.

10. A metal bending machine comprising an I-beam, means at the ends of said beam for supporting the article to be bent, a carriage suspended from the lower flanges of 40 said beam and movable along the same, power means mounted on said carriage, pulling means connected to said power means and also movable with said carriage, bending means connected to said pulling means and 45 engaging over the top of said article, anvil blocks mounted between the top of the beam and the underside of said article at each side of said bending means, means for moving said carriage with said pulling means, and 50 power means and bending means along said article.

11. A metal bending machine, comprising a main longitudinal support having end pillow blocks to support the article to be bent, 55 a carriage mounted to slide longitudinally along the support, vertical pull bars mounted to slide vertically through the carriage at either side of the said support, a detachable, transverse bending bail carried at the upper ends of the bars and adapted to engage the work, controllable means supported by the carriage for forcing the bars downwardly, means for shifting the carriage along the longitudinal support, abutment blocks adjustable with the carriage, and arms for sup-

porting the blocks and permitting the same to be swung in a horizontal plane into or out of engagement with the longitudinal support and the work.

12. In a metal bending machine, the combination with a beam, means at the ends of said beam for supporting the article to be bent, bending means having an element engaging over the top of said article, swingable anvil blocks mounted on top of the beam and engaging the underside of said article at each side of said bending means, and connecting devices between the bending means and said anvil blocks, said connecting devices being flexibly connected to permit the bending means to be moved up and down without affecting the position of the anvil blocks.

13. In a metal bending machine, the combination with a beam, means at the ends of said beam for supporting the article to be bent, bending means having an element engaging over the top of said article, anvil blocks mounted on top of the beam and engaging the underside of said article at each side of said bending means, and connecting devices between the anvil blocks and said bending means whereby the bending means may be given an up-and-down movement to 85 bend the article without affecting the position of the anvil blocks, and whereby said blocks may be swung laterally in a horizontal plane from beneath the said article and supported when it is desired to bend said article from end to end.

14. In a metal bending machine, the combination of a beam, means at the ends of said beam for supporting the article to be bent, bending means having an element engaging over the top of said article, means for mounting said bending means so that the same may be moved longitudinally along said article, anvil blocks mounted on top of said beam and engaging the underside of said article at each side of said bending means, and connecting devices between said bending means and said anvil blocks for permitting the bending means to be moved vertically without affecting the position of 90 said anvil blocks, and also permitting said anvil blocks to be moved laterally in a horizontal plane out of engagement with said article and supporting the same when it is desired to bend said article from end to end, said connecting devices including two distinct pivotal movements, one at right angles to the other.

15. A metal bending machine comprising a beam, means at the ends of said beam for supporting the article to be bent, spaced anvil blocks mounted on top of said beam and engaging the underside of said article, bending means located between said anvil blocks and having an element engaging over the 115 top of said article, means for flexibly con-

necting the blocks to the bending means, and means for turning said article, all of said means, except the element engaging over the top of said article, being located below the latter so that an operator may sight along said article without having his vision interfered with by any part of the bending machine.

16. A bending machine comprising an elongated supporting beam, a frame mounted beneath the beam and slidably connected thereto, a depending pressure cylinder carried by the frame at one end thereof and having a vertically movable piston therein, hangers carried by the other end of the frame, a lever terminally connected to the lower ends of the hangers and to the piston rod respectively, vertical pull bars connected at their lower ends to the said lever at an intermediate point of the same and arranged in straddling relation to the beam, a bending bail detachably hinged at each end to the upper ends of the pull bars and adapted

to be swung to one side or the other, terminal work supports mounted on the beam to support a pipe or bar to be straightened, means for turning the pipe or bar on the supports, means for reciprocating the carriage or frame along the beam, means for supplying and controlling fluid pressure within the cylinder, anvil blocks adapted to rest upon the beam in equal spaced relation to the bail and to support the pipe or bar after the bail has been hooked over the same, and swinging arms each having one end flexibly connected to one of the blocks and the other end flexibly connected to the upper end of one of the pull bars to permit the blocks to be swung to one side and to permit downward movement of the bail when pressure is admitted to the upper end of the cylinder.

In testimony, that I claim the foregoing as my own, I have hereto affixed my signature.

WILLIAM P. WOODS.
